UNITED STATES PATENT OFFICE

129,931

DESIGN FOR A CASING FOR A LIQUID MEAS-
URING APPARATUS

William F. Schultz, Ripon, Wis.

Application May 28, 1941, Serial No. 101,203

Term of patent 14 years

To all whom it may concern:

Be it known that I, William F. Schultz, a citizen of the United States, residing at Ripon, in the county of Fond du Lac and State of Wisconsin, have invented a new, original, and ornamental Design for a Casing for a Liquid Measuring Apparatus, of which the following is a specification, reference being had to the accompanying drawing, forming part thereof.

In the drawing:

Fig. 1 is a side elevation of a casing for a liquid measuring apparatus embodying my new design.

Fig. 2 is a horizontal section taken on line 2—2 of Fig. 1.

Fig. 3 is a vertical section taken on line 3—3 of Fig. 1.

The dominant feature of the design consists in the portion shown in full lines in the drawing.

I claim:

The ornamental design for a casing for a liquid measuring apparatus, as shown and described.

WILLIAM F. SCHULTZ.
